REFLEX TYPE LOUD-SPEAKER CABINET

Stanley M. Kincart, Cincinnati, Ohio

Application September 12, 1946, Serial No. 696,581

6 Claims. (Cl. 181—31)

1

This invention relates to a loud-speaker tone chamber and is particularly useful in connection with loud-speakers of the cone type, whether the speaker be of the permanent magnet or dynamic type.

A speaker of the cone type produces sound vibrations of the cone element which set the adjacent air into vibration. It is a characteristic of a cone type loud-speaker that sound is emitted from the rear of the cone as well as from the front. In conventional speaker systems, various means have been tried and adopted for muffling or damping the tone emitted from the rear of the speaker so as not to interfere with tones emanating from the front of the speaker.

It is an object of my present invention to improve the characteristics of a loud-speaker of the cone type by utilizing sound emitted from the rear of the cone and causing it to travel through certain paths and be emitted toward the front so as to combine with and reinforce the tones emitted from the front of the speaker in a normal manner.

It is another object of my invention to cause the paths for tones, emitted from the rear of the speaker to be elongated, so that for any frequency, and particularly frequencies in the low register, there will be paths which are one-half wave in length, or odd multiples thereof.

In general the objects of my invention include the provision of a tone chamber for a loud-speaker in which tones from the front possess a greatly improved response in the low registers as well as improved high tones.

These and other objects of my invention which will be pointed out hereinafter, or which will be apparent to one skilled in the art upon reading these specifications, I accomplish by that certain construction and arrangement of parts of which I shall now describe an exemplary embodiment. Reference is made to the drawings forming a part hereof and in which—

Fig. 1 is a front elevational view of a device embodying my invention.

Fig. 2 is a horizontal cross sectional view thereof.

While my invention may be carried out in a number of ways and may embody no more than the tone chamber itself for uses where the speaker is confined (as behind a motion picture screen for sound movies) I have shown it in the present case as being incorporated into a bar, such as may be found in small restaurants and bars as well as in recreation rooms in private homes. This particular embodiment, of course, forms no limitation upon my invention.

A bar or suitable cabinet to contain the speaker and tone chamber is indicated at 10. It preferably has a front panel and lateral panels ex-

2

tending rearwardly and at an angle as indicated at 11. In some installations, as for example behind a motion picture screen, the panels 11 should be coplanar with the panel 10, by extension of the panels 22. The side walls and rear of the cabinet are indicated by the broken lines 12 and 13 since the particular form of these panels is immaterial. The top and bottom baffles of the tone chamber are indicated at 12a and 12b, respectively.

Substantially centrally of the front panel 10, I provide a suitable grille or series of slots indicated generally at 14. Behind the grille 14, upon a sub-baffle 15, I mount a loud-speaker 16 having a cone 17. It will be clear that tone emanating from the front of the cone 17 will issue through the grille 14 in conventional manner.

In order to utilize tone emanating from the rear of the cone I provide passages in communication with the rear of the cone and leading to grilles or apertures 18 in the panels 11. It will be noted that the grilles 18 are disposed at an angle pointing outwardly from the axis of the cone 17, so that tones from the speaker as a whole are not projected only directly forward, but also are projected toward the side. I have found that a speaker according to my present invention is quite directional in its characteristics with maximum volume projected straight forward, a decreasing volume outwardly substantially to a 45° angle and with practically no tones projected directly to the sides or to the rear.

Directly behind the speaker, I provide a pair of angularly disposed baffles 19 meeting in an edge 20 and serving to deflect tones which are emitted directly to the rear respectively to the right and to the left. Extending outwardly from the baffles 19 are a pair of rear baffles 21 which are substantially parallel with the front of the structure, and from the baffles 21, there extend forwardly a pair of inclined baffles 22. The baffles 21 and 22 serve to reflect forwardly tones which are projected to the rear from the cone 17. On each side of the loud-speaker cone I provide baffles 23, which serve to deflect toward the rear any tones which are emitted directly toward the side from the cone 17. The baffles 23 are substantially parallel to the baffles 19. Extending forwardly from the rear edges of the baffles 23, I provide a pair of baffles 24 which are substantially parallel to the baffles 22.

It will thus be seen by referring to the broken lines *x* and *y* how tones projected from the rear of the cone may be deflected about so as to emerge through the grille 18, and it will be seen that these paths are considerably longer by virtue of the angular construction of the baffles.

It will also be noted that a substantial space

is provided between the edge 20 and the rear of the speaker 16. This permits tones which are projected from one side of the speaker to cross over behind the speaker, so as to emerge through the grille 18 on the opposite side as indicated, for example, by the broken line 2. It will be seen that the tones which cross over have a much greater effective length of path than those which do not cross over. A range of frequencies for a speaker to provide good fidelity is from 30 to 10 thousand cycles per second. Since the wave length of a tone can be determined by dividing the velocity of sound by the frequency, it may be readily calculated that the length of a half-wave of a 30 cycle per second tone is about 218 inches. For 50 cycles per second tones, the length of a half-wave is about 130 inches and for 100 cycle per second tones, it is about 65 inches. At the other end of the scale, we find that for tones of 10 thousand cycles per second, the length of a half-wave is .66 inch and for 5 thousand cycles per second, it is 1.31 inches. From the above it is clear that there is a considerable range in half-wave length between tones of 30 cycles per second on the low end and 10 thousand cycles per second on the high end. It will also be understood that by virtue of the infinite number of directions in which tones may be reflected from the back of the cone 17, there will be for any individual frequency a number of paths which are one-half wave or a multiple thereof in length. Such tones will strengthen and reenforce tones being projected from the front of the speaker. The general effect apparent to the hearing when listening to a loud-speaker according to my invention is that the high tones are sharper and clearer, while the low tones are well rounded, resonant, and free from objectional vibrations and booming. The tonal effects are also improved by the sounding board effect of the various baffles which are used.

While dimensions are not highly critical, I have determined that in general the distance between centers of the lateral grilles should be about five times the diameter of the speaker for best results; also that the depth of the tone chamber should be about one-quarter of the total width. These figures set the practical minimum dimensions, while the practical maximum dimensions are about double the above. Thus, for example, with a 5 inch speaker the minimum width should be about 25 inches, while the maximum width might be as high as 50 inches with the depth of the tone chamber ranging from about 6 inches to about 12 inches; and with a 15 inch speaker the minimum width would be about 75 inches and the maximum width about 150 inches with the depth ranging from about 19 inches to about 38 inches.

While I have shown and described my invention as having two diametrically opposed branches, it will be clear that any number of branches could be symmetrically disposed about the axis of the cone, so as to constitute a polygonal or even a circular tone chamber. A circular tone chamber may be considered as a revolution of Fig. 2 about the axis of the cone.

For some special purposes it may be desirable to add one or more small supplementary speakers and these may be mounted between the baffles 23 and 24, as indicated in broken lines at 25 in Fig. 2 in which supplementary grilles or apertures could be provided as at 26 in Fig. 1. It

may also be desirable to use more than one speaker behind the grille 14.

It will be understood that numerous modifications may be made without departing from the spirit of my invention and I therefore do not intend to limit myself except as pointed out in the claims which follow.

Having now fully described my invention what I claim as new and desire to secure by Letters Patent is:

1. A tone chamber for a cone type loud-speaker, comprising a baffle upon which said speaker is mounted, said baffle having an aperture coaxial with said speaker for emission of tones to the front, a pair of angularly disposed baffles behind said speaker, said baffles meeting in a dividing edge substantially centrally behind said speaker, a pair of angularly disposed baffles one to each side of said speaker and extending rearwardly in substantial parallelism with the respective first mentioned angular baffles which are on the same side of the speaker axis, a pair of rear baffles to each side of said first mentioned angular baffles, a pair of baffles extending forwardly from said rear baffles, and a pair of baffles parallel to said forwardly extending baffles extending forwardly from said rearwardly extending baffles, said various baffles constituting a pair of diametrically opposite reflective paths for tones emitted from the rear of said speaker, and openings for the emission of sound from said paths.

2. A tone chamber according to claim 1, in which said dividing edge is rearwardly spaced from the rear of said speaker, whereby tones emitted from one side of said speaker and reflected from said angularly disposed baffles on either side of said speaker may cross over behind said speaker and issue from the reflective path on the opposite side of said speaker, thereby traveling an effectively longer path.

3. A tone chamber according to claim 1, in which the distance between centers of said openings is on the order of five times the diameter of said speaker.

4. A tone chamber according to claim 1, in which there are top and bottom baffles for said chamber, and in which the depth of said chamber is on the order of one quarter its length.

5. A tone chamber according to claim 1, in which the distance between centers of said openings is on the order of five times the diameter of said speaker.

6. A tone chamber according to claim 1, in which the distance between centers of said openings is on the order of five times the diameter of said speaker, said chamber being provided with top and bottom baffles, and the depth of said chamber being on the order of one quarter its length.
